ELECTRIC DISCHARGE TUBE

Selfrid Gunnar Öhlund, Enskede, Sweden, assignor to Lumalampen Aktiebolag, Stockholm, Sweden, a corporation of Sweden

Application October 7, 1948, Serial No. 53,359
In Sweden March 20, 1945

1 Claim. (Cl. 176—122)

1

This invention relates to a fluorescent electric discharge tube capped at one end of the tube envelope and having two preheatable electrodes disposed, one close to the capped end and the other close to the top end, respectively of the tube envelope. The electrodes are carried by a common stem having a tubular extension in the middle of the tube envelope enclosing connectors to the top electrode.

An object of the invention is to conceal the inner parts of the discharge tube when radiating. For this purpose fluorescent coatings are provided within the tube envelope as well as on the tubular extension, said coatings participating in the transformation of the radiation produced by the discharge and thus making the interior of the tube invisible and without shaded contours. To further promote a homogeneously radiating surface of the tube and prevent blackening of the fluorescent coating on the top of the tube, the top electrode is shielded from said tube end by a sputtering projector facing this tube end.

To carry the electrodes of a discharge tube by a common support is already known in itself; but in discharge tubes for lighting purposes this construction has only been used in connection with discharge tubes with comparatively intensely shining surface, and therefore any inconvenient effect from this construction of the electrode system is not experienced. Carrying of the electrodes by the common support is, moreover, effected outside the discharge vessel proper, which in its turn is arranged in a surrounding protective envelope. In discharge tubes for lighting purposes with less intensely shining surface and with the electrode carrying devices arranged in the discharge vessel proper the electrode system would cause a disturbing effect with regard to the emission of light and in many cases render impossible the practical use of the tube. By designing the tube according to this invention the electrode system can be hidden without difficulty and a very advantageous source of light can be obtained. As compared with hitherto commonly used vapour lamps, which are equipped with sockets at both ends of the tube, it is now possible to obtain a single-socket discharge tube, which is decorative and suitable in many respects.

The invention is illustrated by a type of design shown in the accompanying drawing, and further to the description of this tube, additional characteristic details and objects of the invention will be given.

The discharge tube as shown consists of a tubular envelope 7, melted together at one end, the other end being closed by stem 3. Into this stem

5 3 are sealed the connectors 4 for the lower electrode 2 and the connector 6 for the upper electrode 11. In order to extend the discharge path as much as possible over the discharge tube, the connectors 4 are suitably bent down so that the lower electrode 2 is close to the bottom of the tube, and the connectors 6 are so long that the upper electrode 11 is close to the tube top. The inside of the tube is covered with a fluorescent coating 8. The connectors 6 to the upper electrode are surrounded by a glass tube 5 slid over these connectors, which at the lower end is sealed to the stem 3 and at the upper end forms a pinch 10. On the glass tube 5 a fluorescent layer is applied. The upper electrode is covered by a sputtering protector 13 in the shape of a hood or the like, carried by a supporting wire 12 from pinch 10 of glass tube 5. The sputtering protector prevents the top of glass cover 7 from being blacked by material disintegrated from electrode 11. A similar protector may also be arranged at the lower electrode. For attaching the lamp in a holder, the lower end is fitted with a socket 1, in which a glow relay or similar auxiliary device for lighting the vapour lamp may be arranged.

25 26 What I claim is:

27 A fluorescent electric discharge lamp comprising a tubular candle-like envelope integrally closed at one end and capped at the opposite end 30 by a mounting socket, two preheatable electrodes in said envelope, one adjacent to each end thereof, said electrodes being carried by a common stem having a tubular extension extending to a place adjacent to the closed end of the envelope, 35 said extension enclosing conductors for the electrode at the closed end of the envelope, said closed end being protected by a shield disposed between said closed end and the adjacent electrode, and the inside of said envelope inclusive of the closed end thereof as well as said tubular extension being provided with fluorescent coatings for concealing the contained parts of the lamp while radiating.

SELFRID GUNNAR ÖHLUND.
